UNITED STATES PATENT OFFICE.

WILLIAM LOACH, OF OSHAWA, ONTARIO, CANADA, ASSIGNOR TO THE PEDLAR PEOPLE LIMITED, OF OSHAWA, ONTARIO, CANADA.

MACHINE FOR MAKING METAL FABRIC.

1,196,064.

Specification of Letters Patent. Patented Aug. 29, 1916.

Original application filed November 2, 1915, Serial No. 59,311. Divided and this application filed February 28, 1916. Serial No. 81,053.

To all whom it may concern:

Be it known that I, WILLIAM LOACH, a subject of the King of Great Britain, and resident of Oshawa, in the Province of Ontario, Dominion of Canada, have invented 5 certain new and useful Improvements in Machines for Making Metal Fabric, of which the following is the specification.

This invention relates to an improved machine for making metal fabric, and the objects of the invention are to enable metal fabric having expanded portions with connecting strips of an improved character to be turned out rapidly and at low cost.

15 Further objects are to strengthen unexpanded connecting strips to prevent breaking of the strands at the point where the expanded portion connects with the unexpanded portion and to provide for shortening of the unexpanded section to compensate with the expanded section.

According to the present invention, the unexpanded portions are shortened simultaneously with the expanding of the other portions and in a further operation the unexpanded portions are strengthened by upsetting corrugations formed therein.

Further features and objects of the invention will appear as the specification proceeds.

In the drawings, Figure 1 is a side elevation of a machine for performing the principal operation of the method. Fig. 2 is a front view of the same partially in section. Fig. 3 is a sectional detail through a pair of dies used to finish the product. Fig. 4 is a front elevation of a set of dies forming the ribs in the product. Fig. 5 is a front elevation of the first set of rollers. Fig. 6 is a sectional detail through the feeding rolls. Fig. 7 is a sectional detail of the feeding rolls. Fig. 8 is a plan view of the metal blank after it has received the first slitting operation. Fig. 9 is a section on the line 2-2 of Fig. 8. Fig. 10 is a perspective view of the product after the first step in the expansion. Fig. 11 is a plan view of the product after it has expanded and has the first rib formed therein. Fig. 12 is a section 50 through the product shown in Fig. 11. Fig. 13 is a sectional view through the final product.

In the drawings like characters of refer-

ence indicate corresponding parts in all figures.

The process uses as raw material strips of sheet metal of any desired and convenient gage, such as at present used for the manufacture of which is known as "expanded metal". These strips are first slit 60 in the usual way prior to expansion, the slitting operation being accomplished on any suitable rotary cutter, the product as it comes from these slitting rollers being shown in Figs. 10 and 11 of the drawings. 65

It will be seen that the strip A is formed with unslit or plain portions 10 and slit portions 11, said slit portions being designed to be expanded in the manner hereinafter described.

70 The next operation is the expansion which is accomplished by passing the slit strip A between pairs of laterally separated rollers having their peripheries radially separated. The machine for this purpose is shown in 75 the drawings and will be briefly described.

The process or method is covered by my copending application Serial No. 59311 filed November 2nd, 1915 of which this is a division.

80 The machine illustrated comprises a plurality of pairs of rotary dies B, C, D, E and F mounted on shafts 12 and 13. The shaft 13 is journaled in suitable bearings in the side frames G and H while the shaft 12 is 85 journaled in suitable sliding bearings 15 which are adapted to be adjusted in position by adjusting screws 16 whereby the shaft 12 with the dies thereon may be adjusted to and from the shaft 13. 90

The dies are laterally separated from each other as indicated and one of the dies of each pair are free on the shaft, thus for instance in the pair of dies B the die 17 is connected to and rotates with the shaft 12 while 95 the die 18 is loose on the shaft 13. In the next pair the die 20 will be connected to the shaft 13 while the die 21 is loose on the shaft 12. In the pair D the die 22 will rotate with the shaft 12 while the die 23 is free on the shaft 13. In the pair E the die 24 will rotate with the shaft 13 while the die 25 is free on the shaft 12. In the pair F the die 26 will rotate with the shaft 12 while the die 27 is free on the shaft 13. 100

105 The shafts 12 and 13 are rotated by con-

venient means. As shown, a gear 28 on the shaft 13 is adapted to mesh with a pinion 29 on a counter shaft 30 journaled in the frame and carrying a gear 31 meshing with a pinion 32 on a counter shaft 33 which carries a driving pulley 34.

The dies are formed with intermeshing teeth adapted to form corrugations of a convenient size in the plain portions of the strips. The strip to be expanded is fed to the rotary dies from between a set of feeding rollers H situated a distance in advance of the dies and midway between them. This set of feeding rollers includes lower rollers 35 mounted on the shaft 36 and upper adjustable rollers 37, each of said adjustable rollers being supported in a suitable yoke 39 which is adjustably connected to a cross bar 40 by means of a bolt 41 extending through the slot 42 and also by means of adjusting the screws 43 extending through the top of the yoke into the cross bar. The rotary dies are laterally separated a distance which corresponds to the plain portions 10 in the strips.

As the peripheries of adjacent rollers are separated from each other in a radial direction it will be seen that the portion 11 of the strips will be expanded between them to assume the formation shown in Fig. 10. At the same time the corrugations will be formed in the plain portions 10 which will shorten said plain portions to correspond with the lengthwise shortening which takes place in the expanded portions as they are expanded.

The next operation is the formation of longitudinal ribs in the corrugated portions which is accomplished by passing the strip 40 through cooperating dies L and M mounted on the shafts N and O. These dies are of the form shown in Fig. 4 and are adapted to form longitudinal ribs in the corrugated portion which will serve to strengthen the same. These corrugations may be increased in successive sets of dies Q, R, and S, T and may be finally caused to produce the product shown in Figs. 11 and 12. To finally finish the product, the ribs 40' appearing in the product shown in Figs. 11 and 12 are adapted to be closed somewhat and to have the corrugations pressed out to a certain extent which will upset the material to increase the thickness of and strengthen the unexpanded portion. This is most conveniently accomplished in a hydraulic press by the use of the dies such as shown in Fig. 3, the upper die 41' having a tongue 42' adapted to enter the lower die 43', which lower die is formed with pivoted wings 44 and 45 normally held a short distance above the base piece 46 by springs 47 and 48 and being designed to be closed down against the tongue when the die 41' moves downwardly. In practice the die 41' will be con-

nected to the movable part of a hydraulic press and strips of the product of convenient length, say sixteen feet will be placed in position in it and the die operated to close the rib 40' and at the same time upset the 70 corrugations.

The product just described has many advantages, in particular the simultaneous shortening and expansion avoids any undue strain in the various parts of the product 75 and the final upsetting of the corrugations gives increased strength to the non-expanded portion, and in fact may be caused to increase the gage of the metal in the unexpanded portion.

As many changes could be made in the above construction and many apparently widely different embodiments of my invention, within the scope of the claims, constructed without departing from the spirit 85 or scope thereof, it is intended that all matter contained in the accompanying specification and drawings shall be interpreted as illustrative and not in a limiting sense.

What I claim as my invention is:

1. A machine for the purpose specified comprising a plurality of pairs of corrugating dies, one die of each pair being free and the peripheries of the adjacent dies being radially separated to cause the fabric to be expanded diagonally between them.

2. A machine for the purpose specified comprising a plurality of pairs of corrugating dies, one die of each pair being free and the peripheries of the adjacent dies will be radially separated to cause the fabric to be expanded diagonally between them, and a plurality of other rotary dies adapted to form ribs in the corrugated portions of the strip.

3. A machine for the purpose specified comprising a series of pairs of rollers placed side by side, the periphery of adjacent pairs of rollers being separated in a radial direction whereby the material passing through the rollers is expanded in a diagonal direction between them.

4. A machine for the purpose specified comprising a series of pairs of rollers placed side by side, the periphery of adjacent pairs of rollers being separated in a radial direction whereby the material passing through the rollers is expanded in a diagonal direction between them, one roller of each pair being free.

5. A machine for the purpose specified comprising a series of corrugated roller dies placed side by side, the periphery of adjacent pairs of dies being separated in a radial direction whereby the material passing through the dies is expanded in a diagonal direction between them.

6. A machine for the purpose specified comprising a series of pairs of rollers placed side by side, the peripheries of adjacent

rollers being radially separated and the rollers being spaced apart whereby the material passing through them will be expanded between them, and feeding means

5 adapted to feed the material medially between the rollers.

7. A machine for the purpose specified comprising a series of pairs of rollers placed side by side, the peripheries of adjacent rollers being radially separated and the rollers being spaced apart whereby the material passing through them will be expanded between them, and feeding means adapted to feed the material medially between the rollers, said feeding means comprising a pair of rollers.

8. A machine for the purpose specified comprising a series of pairs of rollers placed side by side, the peripheries of adjacent rollers being radially separated and the rollers being spaced apart whereby the material passing through them will be expanded between them, and feeding means adapted to feed the material medially between the rollers, said feeding means comprising a plurality of pairs of independently adjustable feeding rollers.

9. A machine for expanding a sheet of metal having slitted and unslitted portions, comprising feeding means adapted to hold the sheet, and means for engaging and carrying alternate unslitted portions away from the plane of the sheet on opposite sides thereof.

35 10. A machine for expanding a sheet of

metal having slitted and unslitted portions comprising means for separating the unslitted portions in a diagonal direction while feeding them longitudinally.

11. A machine for expanding a sheet of metal having slitted and unslitted portions comprising means for feeding the sheet longitudinally, and means operated during feeding of the sheet for carrying the unslitted portions away from each other in a diagonal direction alternately on opposite sides of the sheet.

12. A machine for expanding a sheet of metal having slitted and unslitted portions comprising means for drawing the unslitted portions away from each other while shortening the length thereof.

13. A machine for expanding a sheet of metal having slitted and unslitted portions comprising means for drawing the unslitted portions apart and simultaneously corrugating them transversely.

14. A machine for expanding a sheet of metal having slitted and unslitted portions comprising means for shortening the unslitted portions longitudinally while transversely expanding the laterally adjacent slitted portions.

In witness whereof I have hereunto set my hand in the presence of two witnesses.

WILLIAM LOACH.
